ABSTRACT: A photoelectric printer for printing the characters from a family having a large number of characters, such as the Japanese or Chinese alphabet. An elongated belt having one reproduction of each character thereon with a separate binary code for each character, located adjacent each character, is driven along a row of a photosensitive recording media. A plurality of printing lamps are positioned over the belt with one lamp located above each column of characters to be printed. Each printing lamp has a sensor for sensing the binary code on the belt as the belt is driven along the row of the photosensitive recording material. The binary code of each character to be printed in each column of the row is recorded beforehand in a buffer storage stage, and the output of each sensor is compared with the recorded code for each column. When the correct code is sensed for a column, the printing light is flashed and that character is printed on the photosensitive recording media. After the belt cycles once along the row, the recording media is then stepped to the next row where the printing process is repeated.

1
PRINTER

The present invention relates to high speed electronic printers.

Print-out facilities utilized in conjunction with today's high-speed computers have been for the most part relatively slow and cumbersome relative to the computer operations themselves. The problem is compounded where hundreds or thousands of different characters or symbols are to be rapidly printed. For example, it is desirable to rapidly print-out a line at a time of characters selected from a group of over 4,000 Japanese characters. Satisfactory solutions to the problem of rapidly and economically typing, type-setting and printing in the Japanese or Chinese languages have not as yet emerged.

Accordingly it is the principal object of the present invention to provide a new and improved high-speed electro-optical printer.

It is a further object of the present invention to provide a novel, high-speed printer particularly adapted to rapidly and economically print or typeset a line or a column at a time in the Japanese or Chinese languages.

Other objects and advantages of the present invention will become apparent as the following description, taken in conjunction with the drawings, proceeds.

FIG. 1 schematically discloses a preferred embodiment of the present invention.

FIG. 2 discloses a side view of a portion of the system of FIG. 1.

FIG. 3 discloses a portion of the character belt.

In accordance with the present invention, an elongated belt bearing transparent indicia of characters and associated identification code designations is driven over a photosensitive recording media. A plurality of flashing circuits are positioned over the elongated belt, one circuit for each row of characters to be printed on the media, light produced by each flasher passes through transparent indicia of a selected character to record the selected character on the media. A code comparator is associated with each flashing circuit and causes its associated flashing circuit to flash when the sensed character identification code on the belt and under the flashing circuit is equal to a character selection address code, thereby to print the selected character under the particular flasher in the desired row of characters. The address codes may be generated by a conventional keyboard encoder or a computer and are inserted sequentially into a plurality of buffers stores, each of which addresses an associated comparator. Since a match will occur between each address code and the identification code of each selected character impressed on the belt once during each belt cycling interval and since the belt and flashing circuits are operated at high-speed, rapid column or line at a time print-out is obtained. By increasing the length of the belt selective print-out of virtually any number of characters or other symbols is attainable.

Referring now to FIG. 1, a photographic film recording media 1 is provided which is supplied by supply roll 2 and passes over print roll 3 as shown in the drawing. Character belt 4 passes about belt rollers 5, 6, 7 and 8 and is driven by belt motor 9 in the direction indicated by arrow 11. As indicated in FIG. 3 character belt 4 includes character track 12 and identification code track 13. Area 14 has a particular transparent Japanese character manifested therein. Whereas area 16 contains that identification code which identifies only its associated character in area 14. This code could be in binary form where each digit is manifested by a transparent or opaque subarea. In the alternative, magnetic code markings could also be utilized.

A keyboard encoder 17 is coupled to the input circuit of distributor 18 by means of binary code leads 19. Where the printer is designed to print over 4,000 Japanese characters, 12 code leads are needed to provide the requisite number of binary code bits. When it is desired to print a column of 40 Japanese characters, 40 buffer stores, such as buffer store 21, are coupled to the distributor output circuitry by means of 40 cables, such as cable 22, each having 12 code leads. The out-

2

put leads of each buffer are coupled to the binary comparator of each printing station, such as station 22. Forty printing stations being provided for the entire machine and only one of which is shown. The 12 output leads of buffer 21 are coupled to the first input circuit of binary comparator 23, the second input circuit of which is coupled to 11 pick-up devices 24 by means of cable 26.

Pickup devices 24 may be magnetic reading heads which read magnetically coded code portions or in the alternative 10 could comprise light pipes for reading binary "checker board" patterns. As well known to those skilled in the art, a convertor such as a bank of photodiodes could provide for converting light signals into electrical signals which are thereafter applied to binary comparator 23.

15 Let it be assumed that it is desired to print a Japanese character identified by the binary number 100. The key board is actuated and the binary number 100 is encoded by unit 17 and is inserted into buffer store 21. When the Japanese character having a code portion corresponding to the binary number 100 is positioned below pickup heads 24, an output signal is produced by binary comparator 23 and timer 27 is actuated. Timer 27 is set so that flasher 28 is triggered just as the Japanese character identified by binary code 100 is directly under light pipe 29. The resulting light passes through the transparent portion manifesting the Japanese character to cause this character to be printed upon recording media 1. It is obvious to those skilled in the art that such printing may be effected by conventional photography or xerography.

20 After the actuation of the key or keys which produces the aforementioned binary number 100 to cause insertion of this number into buffer 21 a mark is impressed upon lead 31 and distributor 18 is stepped which in turn results in the next encoded binary number being inserted into the second buffer 25 store, not shown. Lead 31 could be energized by having the operator strike at end of character key or in the alternative a delay device such as a monostable multivibrator could be coupled between encoding leads 19 and lead 31. The output leads of the second buffer store are connected to a binary comparator 30 similar to binary comparator 23 which is part of the second row printing station, not shown, which station is identical to printing station 22. The printing of the second Japanese character is effected in the same manner as the printing of the first character. The distributor is again stepped and the process continues until all characters are printed. Obviously 35 all characters may be encoded before printing takes place by merely providing isolation means between the buffer stores and the binary comparators. When the binary number representing the last character is inserted into the Nth buffer store, "or" gate 32 produces a mark upon its output terminal 33 which sets timer or delay means 34. The timer is adjusted so as to mark its output circuit 36 after a given interval which is longer than the cycling time of character belt 4. The marking of lead 36 causes all buffer stores and distributors 18 to 40 become reset to thereby set the stage for the printing of a new column of characters. The marking of lead 36 also causes stepping motor 37 to rotate through a given angle which advances recording media 1 and causes an additional increment of paper to be advanced from supply row 2.

45 Details of the key board encoder 17 are omitted since such units are well known to those skilled in the art. An example of such a unit is disclosed in U.S. Pat. No. 2,408,754 to G. L. Bush. Obviously if 4,000 Japanese characters are being printed 4,000 keys would not be provided. A relatively small number of keys each having particular character segments impressed thereon would be utilized for many characters only two such keys need be sequentially actuated. The actuation of the first key could impress a binary code on a first subgroup of 50 the aforementioned group of leads 22 while the actuation of the second key thereafter would impress another binary code on the second subgroup of the group of leads 22 and so on.

55 In summary the printer of the present invention can selectively print Japanese from 4,000 or more characters almost as rapidly as a high speed printer can manipulate the key board.

Should it be desirable to print from a group of symbols or characters having considerably more than 4,000 members all that is necessary is that character belt 4 be made longer. It should be understood that a digital computer output or any other source of digital data could readily be substituted for the key board encoder. 5

While there has been described what is at present considered to be the preferred embodiment of this invention, it will be obvious to those skilled in the art that various changes and modifications may be made therein without departing from the invention and it is, therefore, intended in the appended claims to cover all such changes and modifications as fall within the true spirit and scope of the invention. 10

We claim:

1. A photoelectric printer comprising in combination: 15
  - a. a symbol storage media having only one symbol of each member of every family of symbols recorded thereon, there being only one required family of symbols, said media further having recorded thereon a separate symbol identification code associated with each one of said symbols; 20
  - b. a plurality of sources of electromagnetic radiation for illuminating said storage media;
  - c. a recording media sensitive to said electromagnetic radiation optically coacting with said symbol storage media; 25
  - d. means for moving said symbol storage media and said recording media relative to one another;
  - e. means for selectively detecting one of said symbol identification codes for each symbol to be recorded on said recording media comprising, a source of symbol address codes, a plurality of buffer stores coupled to said source of symbol address codes, symbol identification code reading means coacting with symbol storage media for reading said symbol identification codes associated therewith, and a plurality of code comparators each having a first input circuit coupled to the output circuit of an associated buffer store and having a second input circuit coupled to the output circuit of one of said associated identification code reading means, said comparator having an output coupled to said means for activating a selected source; and 30
  - f. means for activating a selected source of said plurality of sources of radiation upon said detection to print one of said symbols on said recording media. 40
2. The combination as set forth in claim 1 wherein said means for activating a selected source includes a variable timing device for accurately controlling the flash instant of the source with respect to the movement of said symbol storage media relative to said recording media. 45
3. Apparatus as set forth in claim 1 wherein said symbol storage media comprises an elongated tape.
4. Apparatus as set forth in claim 2 wherein said symbol storage media comprises an elongated tape.
5. Apparatus as set forth in claim 1 wherein said means for moving includes first means for moving said recording media and second means for substantially continuously moving said symbol storage media in a direction transverse to the direction of movement of said recording media. 55
6. Apparatus as set forth in claim 2 wherein said means for moving includes first means for moving said recording media and second means for substantially continuously moving said symbol storage media in a direction transverse to the direction of movement of said recording media. 60
7. A photoelectric printer comprising in combination: 65
  - a. a symbol storage media having only one symbol of each member of every family of symbols recorded thereon, there being only one required family of symbols, said media further having recorded thereon a separate symbol identification code associated with each one of said symbols; 70
  - b. a plurality of sources of electromagnetic radiation for illuminating said storage media;
  - c. a recording media sensitive to said electromagnetic radiation optically coacting with said symbol storage media; 75

d. means for moving said symbol storage media and said recording media relative to one another comprising first means for moving said recording media and second means for substantially continuously moving said symbol storage media in a direction transverse to the direction of movement of said recording media;

e. means for selectively detecting one of said symbol identification codes for each symbol to be recorded on said recording media; and

f. means for activating a selected source of said plurality of sources of radiation upon said detection to print one of said symbols on said recording media.

8. A photoelectric printer comprising in combination:

- a. a symbol storage media comprising an elongated tape having only one symbol of each member of every family of symbols recorded thereon, there being only one required family of symbols, said media further having recorded thereon a separate symbol identification code associated with each one of said symbols;
- b. a plurality of sources of electromagnetic radiation for illuminating said storage media;
- c. a recording media sensitive to said electromagnetic radiation optically coacting with said symbol storage media;
- d. means for moving said symbol storage media and said recording media relative to one another comprising first means for moving said recording media and second means for substantially continuously moving said symbol storage media in a direction transverse to the direction of movement of said recording media;
- e. means for selectively detecting one of said symbol identification codes for each symbol to be recorded on said recording media; and
- f. means for activating a selected source of said plurality of sources of radiation upon said detection to print one of said symbols on said recording media.

9. A character printer comprising in combination:

- a. a symbol storage media having only one symbol of each member of every family of symbols recorded thereon, there being only one required family of symbols, said media further having recorded thereon a separate symbol identification code associated with each one of said symbols;
- b. a recording media subject to recordation of a plurality of said symbols;
- c. means for moving said symbol storage media and said recording media relative to one another;
- d. means for selectively detecting one of said symbol identification codes comprising, a source of symbol address codes, a plurality of buffer stores coupled to said source of symbol address codes, symbol identification code reading means coacting with symbol storage media for reading said symbol identification codes associated therewith, and a plurality of code comparators each having a first input circuit coupled to the output circuit of an associated buffer store and having a second input circuit coupled to the output circuit of one of said associated identification code reading means, said comparator having an output coupled to said recording means; and
- e. recording means responsive to said means for selectively detecting one of said symbol identification codes to record the symbol on said recording media which corresponds to said one symbol identification code.

10. Apparatus as set forth in claim 9 wherein said recording means includes a variable timing device for accurately controlling the timing of said recording means with respect to the relative movement of said symbol storage media and said recording media.

11. A character printer comprising in combination:

- a. a symbol storage media having at least one symbol of each member of a selected family of symbols recorded thereon, said media further having recorded thereon a separate symbol identification code associated with each of said symbols;
- b. a recording media subject to recordation of a plurality of said symbols;

- c. means for moving said storage media and said recording media relative to one another;
- d. said means for moving including first means for moving said recording media and second means for substantially continuously moving said symbol storage media in a direction transverse to the direction of movement of said recording media;
- e. means for selectively detecting one of said symbol identification codes; and
- f. recording means responsive to said means for selectively detecting one of said symbol identification codes to record the symbol on said recording media which corresponds to said one symbol identification code.

5

12. Apparatus as set forth in claim 11 wherein:

- a. said printer is a photoelectric printer;
- b. said recording means includes a plurality of sources of electromagnetic radiation for illuminating said storage media;
- c. said recording media is sensitive to said electromagnetic radiation which optically coacts with said symbol storage media; and
- d. said recording means further includes means for activating a selected source of said plurality of sources of radiation in response to said means for selectively detecting to

15

20

25

- record one of said symbols on said recording media.
- 13. A character printer comprising in combination:
  - a. a symbol storage media having only one symbol of each member of every family of symbols recorded thereon, there being only one required family of symbols, said media further having recorded thereon a separate symbol identification code associated with each one of said symbols;
  - b. a recording media subject to recordation of a plurality of said symbols;
  - c. means for moving said symbol storage media and said recording media relative to one another comprising first means for moving said recording media and second means for substantially continuously moving said symbol storage media in a direction transverse to the direction of movement of said recording media;
  - d. means for selectively detecting one of said symbol identification codes; and
  - e. recording means responsive to said means for selectively detecting one of said symbol identification codes to record the symbol on said recording media which corresponds to said one symbol identification code.
